UNITED STATES PATENT OFFICE

2,484,307

NESTED CYLINDER COOLER

Willard L. Morrison, Lake Forest, Ill.

Application July 10, 1944, Serial No. 544,262

4 Claims. (Cl. 62—129)

1

My invention relates to an improved cooling mechanism.

One purpose is to provide a maximum utilizable cooling surface for the cooling of flowing liquids or gases through a relatively restricted space.

Another purpose is to provide an evaporator having an exterior and an interior primary cooling surface, both subjected to the flow of a liquid or a gas, such as air, to be cooled.

Another purpose is to provide an improved cooling member including a plurality of nested evaporators, each of which has an inner and an outer primary cooling surface.

Another purpose is to provide a cooling member in which the air or liquid to be cooled flows in the same direction along the inner and outer faces of an open ended cylinder, the inner and outer face of such cylinder being substantially entirely direct or primary cooling surface.

Other purposes will appear from time to time in the course of the specification and claims.

I illustrate the invention more or less diagrammatically in the accompanying drawings which indicate various structures in which my invention is employed.

Figure 1 is a plan view of one application of my invention;

Figure 2 is a section on the line 2—2 of Figure 1;

Figure 3 is a section on the line 3—3 of Figure 2;

Figure 4 is a section on an enlarged scale on the line 4—4 of Figure 3;

Figure 5 is a vertical section through a variant application of my invention; section is taken on the line 5—5 of Figure 6;

Figure 6 is a section on the line 6—6 of Figure 5;

Figure 7 is a vertical section through a still further variant of my invention in which it is applied to the cooling of a liquid; and

Figure 8 is a section on the line 8—8 of Figure 4.

Like parts are indicated by like symbols throughout the specification and drawings.

Referring first to the form of Figures 1 to 4, I illustrate a portable air cooling or air conditioning unit. It is shown as including a base 1 and an outer housing having a rear wall 2, a lower front wall 3, lower side or end walls 4 and a bottom wall 5, shown as resting upon the base 1.

I illustrate an open topped intake duct 6 which may be of any suitable shape but is shown as generally rectangular in cross section. It extends to and communicates with a housing 7 on which is positioned a condenser 8 and any suitable motor compressor unit including a compressor indicated as 9 and having a motor 9a driving the com-

pressor 9. Air is delivered from the housing 7 through the discharge duct 11 with its open top 12. Thus air is passed about or through the condenser 8. It will be understood that I may employ any suitable refrigerating circuit, and its details do not of themselves form part of the present invention. However, the motor 9a may drive both the compressor 9 and the fan 10, the fan 10 being effective to draw air down the duct 6 and to discharge it upwardly along the duct 11. In the refrigerating circuit which includes the condenser 8 and the compressor 9 I illustrate an evaporator structure consisting of one or more cylinders, each of which surrounds a space through which the air to be cooled may flow. I illustrate a plurality of nested evaporator cylinders as shown for example generally indicated as A, B, and C in Figures 4 and 8, but a single cylinder may be used. Air may be admitted downwardly about the cylinder or cylinders, the cylinders being illustrated as having their axes generally vertically arranged. In order to direct air about the cylinders, I illustrate a housing which includes the upper front wall 20, side walls 21 and a rear wall which may be continuous with the wall 2. The top wall 22 may be apertured as at 23 to permit air to flow downwardly about the cylinders. In Figure 2 I have illustrated two nests of cylinders. The second nest 20 being understood to be in series with the first nest A, a total of six cylinders being provided in the two nests, arranged in series between any suitable receiver and the return duct to the compressor 9. Cool air flows downwardly in the direction of the arrows in Figures 2 and 3 and may pass out between louvres 24 in the lower part of the upper front wall 20. It will be understood that this structure constitutes merely one example of a cooling unit designed to employ one or more of my evaporators.

Referring to the specific evaporator structure, I illustrate in Figure 4, three nested cylinders each of which includes an outer wall or cylinder 25 and an inner wall or cylinder 26, the walls being sealed together at top and bottom as at 27, 28. They may be welded directly together, or filler rings 27a, 28a may be used. Any suitable means may be employed, within the cylinder, for maintaining a substantially uniform distribution of refrigerant throughout the interior of the evaporator, across the inner face of the outer cylinder 25 and across the outer face of the inner cylinder 26. I may for example use relatively loose rods 28b, gripped between the inner and outer cylinders, but allowing a measure of leakage between

runs. The rods help define a tortuous path for the refrigerant. Thus substantially the entire outer face of 25 and substantially the inner face of 26 constitutes a primary cooling surface. Any suitable ducts 29 may bring liquid coolant from any suitable receiver forming part of the refrigerating circuit, and housed at any suitable point within the housing 7. A duct 30 delivers the coolant from the unit A to the unit B. A duct 31 delivers the coolant from the unit B to the unit C 10 and a duct 32 carries coolant to the outer cylinder of the unit D. Finally, any suitable duct 33 carries coolant from the inner cylinder within D back to the compressor.

It will be realized that I do not wish to be limited to any particular form of evaporator or to any particular number of evaporators. I do, however, provide a highly efficient air cooling means in which one or more cylinders, preferably nested when more than one is used, each having a primary surface both within and without, are arranged in the line of flow of the air to be cooled, the air flowing across both faces of the cylinder or cylinders employed. Thus a highly efficient heat exchange means is provided in which a maximum cooling area is positioned within an air directing duct of minimum cross sectional area. The same principle or structure may be employed for cooling other gases, or liquids.

Any suitable means may be employed for supporting and spacing the cylinders. I illustrate for example generally radial spacing members 34 which are preferably of a material having inefficient heat transfer properties, or including heat insulating portions which actually engage the cylinders A, B, and C, etc.

Referring to the form of Figures 5 and 6, I illustrate a similar nest of cylinders, generally indicated as E, arranged on its side. In that structure I illustrate a base 40 and a bottom housing generally indicated as 41 in which is positioned a condenser 42, a motor 43, a fan 44, a compressor 45, and a receiver 46. Liquid flows from the receiver 46 along the duct 41 to the outer cylinder 48. It flows thence through the intermediate cylinder 49 and the inner cylinder 50 and back along the duct 51 to the compressor 45. 52 is a duct extending from the compressor to the condenser and 53 is a duct extending from the condenser to the receiver. However, the particular refrigerating circuit is not a critical factor.

The fan 44 is effective to cool the condenser coil 42. Air may enter for example through any suitable inlets 41a in the lower compartment and may escape through any other suitable inlets such as the louvres 42b. A second fan 60 delivers air inwardly to the upper housing 61, through any suitable apertures 60a, for passage about the cylinders 48, 49 and 50. This air may be delivered through an air passage 60b which is shown as terminating adjacent the ends of the cylinders. It will be understood that the passage 60b may be extended, in tubular form, along part of the length or along the entire length of the exterior of the outer cylinder 48. In that event the outer cylinder 48 constitutes the liner of a passage through which a fluid flows. It will be understood that any number of cylinders may be employed. I may employ a single cylinder which serves as or defines a tubular space through which the fluid, such as a gas, may flow. The cylinders may be inclined slightly for draining and a pipe 62 is provided for carrying off any condensation. The cooled air is shown as flowing from the ends of the cylinders upwardly through the upper

housing 61. It will be understood however that a wide variety of housings or enclosures may be employed. Also, if a single cylinder, or the outside cylinder of a group, is employed as a duct for directing the air, the outer housing 61 may be omitted, or may be replaced by a surrounding insulating sheath in direct contact with the exterior of the cylinder 48.

Referring to Figure 7, I illustrate a machinery oil cooler. 70 is any suitable base on which is mounted an insulating housing 71, and insulating cover 72. 73 is a supply pipe adapted to deliver the oil or other liquid to be cooled, into a distributing tray 74. I illustrate concentric cylinders 75, 76 and 77 which may be arranged concentrically and vertically as shown. 78 is a duct adapted to deliver any suitable refrigerant for example from the receiver of any suitable cooling circuit. The three cylinders are arranged in series, connected by the ducts 79 and 80. 81 is a return duct from the inner cylinder to any suitable compressor. For example the condenser circuit shewn in Figures 5 and 6, or its equivalent, may be employed. The liquid to be cooled, for example oil used in lubricating machinery, may be permitted to flow through apertures 85 in the bottom of the pan 74. The oil flows down or across the inner and outer faces of the three cylinders and may escape from any suitable collector 86 at the bottom, as by a discharge duct 87. The above structure is given primarily for purposes of illustration, indicating a practical means for cooling a liquid by causing the liquid to flow about or along the opposite faces of one or more evaporator cylinders, both the inner and outer faces of each evaporator cylinder consisting of direct or primary cooling surface.

As an example of a practical method of distributing the refrigerant throughout the interior of the individual cylinders, shown in the various drawings filed herewith, I may employ the system illustrated in my co-pending application 363,743 filed October 31, 1940, United States Patent Office under the title "Method and apparatus for freezing foods," now Patent No. 2,356,779. It will be understood that any other suitable means may be employed for obtaining a substantially uniform distribution of the refrigerant throughout the space defined between the inner and outer wall of each of the cylinders herein described and shown.

It will be realized that whereas I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

For instance, I may employ a single cylinder, or a nest of cylinders, or a plurality of nests of cylinders. I may also use evaporators which are non-cylindrical in form. Each nest may have two or more of such cylinders or evaporators. As a matter of convenience the nests, and the individual cylinders or evaporators in the nests, may be arranged in series in any suitable refrigerating system or circuit. However, this is a matter of illustration and not a critical factor. I may arrange the individual evaporators or the nests of evaporators in vertical position or in horizontal position or in any intermediate position. I may employ any suitable means for di-

recting the air, gas or liquid to be cooled. I may employ forced draft, as shown in the structure of Figure 5 or I may employ natural draft, as shown in the structure of Figures 1 and following.

The use and operation of my invention are as follows:

I provide a cooling unit or evaporator which, basically, includes an inner wall surrounding a space through which the fluid to be cooled may flow and an outer wall surrounding the inner wall. The inner wall and outer wall are sealed together at their ends and are spaced slightly apart, to define a space through which a refrigerant may flow. By employing suitable means for distributing the refrigerant, for evaporation, substantially uniformly throughout the space defined between the inner wall 26 and the outer wall 25, I produce a cooling unit including an evaporator having an outer face and an inner face both of which constitute primary refrigerating surfaces. The refrigerant is separated from the exterior of the evaporator only by the evaporator wall itself. While I illustrate my evaporator as in cylindrical form, it may be made noncylindrical. In use, it may be positioned in the line of flow of a liquid or of a gas. The fluid to be cooled flows both through the space surrounded by the evaporator and along the outer wall of the evaporator. For convenience and efficiency a plurality of evaporators may be nested together, as shown in the drawings. Where a group of evaporators are nested, and are positioned in a duct through which the air or liquid to be cooled flows, there is a maximum of heat exchange in a minimum space. The individual evaporators are strong and will resist high pressures without separate reinforcement. They are easy and economical to manufacture.

My cooling unit lends itself to a wide variety of uses. It may for example be employed in connection with air conditioning. It may be employed in cooling air for refrigeration, as where substances to be chilled or frozen are subjected to the flow of cold air or cold gas. Because of the efficiency of my cooling unit it is admirably adapted for use in situations where a maximum cooling effect must be obtained with a minimum use of space. Thus my unit may efficiently be employed in connection with cooling or air conditioning automotive vehicles and freight or passenger cars. Where my invention is used in connection with refrigerating or air conditioning equipment I can, as above pointed out, employ a circumferentially extending open ended evaporator to define a duct. In that event it will be advantageous to employ an outer insulating coating about the duct. However, where my device is used under circumstances in which its employment as a duct is not necessary, a great deal of cooling surface can be added by permitting both the exterior and the interior surfaces of the evaporator to act on the fluid to be cooled. In the form of Figures 1 and following I may find it advantageous to increase the size of the aperture 23, where a maximum flow and a maximum efficiency is desired, so that room air may flow directly downwardly across the outer surface of the outer evaporator of each of the evaporator groups. Stated broadly, my invention involves employing an evaporator which extends circumferentially about an area which serves as a duct through which a fluid, for example a gas, is caused to flow. The direct

cooling surface may be doubled by permitting the fluid to flow simultaneously about or across the exterior and the interior surface of the evaporator. Nesting additional evaporators within an outside evaporator further multiplies the primary cooling surface to which the fluid is subjected.

It will be understood that the showing of Figures 5 and 6 is diagrammatic and brings out the fact that the circulation of air through the space in which the compressor-condenser is positioned is separate from the circulation of air through the cooling element.

I claim:

1. In a cooling element adapted for use for cooling fluids, a circumferentially extending cylindrical evaporator, a refrigerating circuit in which said evaporator is included, said evaporator comprising an inner and an outer member, said members being spaced apart and being sealed together at their ends, and defining therebetween a space through which the refrigerant flows, means for so directing and distributing the refrigerant against substantially the entire outer surface of the inner member and against substantially the entire inner surface of the outer member, as to cause a substantially even distribution of evaporation effective to maintain substantially the entire inner surface of the inner member and substantially the entire outer surface of the outer member as primary cooling surfaces, the evaporator surrounding and circumferentially defining a space through which a fluid to be cooled may flow, the outer surface of the outer member and the inner surface of the inner member being both exposed to the flow of said fluid to be cooled, a concentric, cylindrical fluid directing duct in which said evaporator is positioned, said duct being outwardly spaced from the outer surface of the evaporator, and means for causing a flow of the fluid to be cooled along said duct and across the inner and outer faces of said evaporator.

2. In a cooling device, a generally cylindrical evaporator surrounding a space substantially open at both ends, said evaporator including inner and outer generally cylindrical walls defining between them a closed space, means for circulating a volatile refrigerant through said space, in direct contact with the inner face of each of said walls, and means for uni-directionally circulating both through the space within the evaporator and about the exterior of the evaporator, a fluid to be cooled, including a surrounding cylindrical housing.

3. In a cooling device, a generally cylindrical evaporator surrounding a space substantially open at both ends, said evaporator including inner and outer generally cylindrical walls defining between them a closed space, means for circulating a volatile refrigerant through said space, in direct contact with the inner face of each of said walls, and means for uni-directionally circulating both through the space within the evaporator and about the exterior of the evaporator, a fluid to be cooled, including a housing surrounding said evaporator and spaced outwardly from the exterior of the outer wall of said evaporator.

4. In a cooling device, a plurality of generally cylindrical, generally concentric evaporators, each surrounding a space substantially open at both ends, each said evaporator including inner and outer generally cylindrical walls defining between them a closed space, means for circulat-

ing a volatile refrigerant through said evaporators, and means for unidirectionally circulating a fluid to be cooled through the spaces between and within said evaporators.
